UNITED STATES PATENT OFFICE.

ELBERT H. SEARLE, OF BRIDGEPORT, CONNECTICUT.

FIRING MECHANISM.

1,393,912.

Specification of Letters Patent.

Patented Oct. 18, 1921.

Original application filed July 22, 1918, Serial No. 245,981. Divided and this application filed May 31, 1919. Serial No. 301,035.

To all whom it may concern:

Be it known that I, ELBERT H. SEARLE, a citizen of the United States, residing at Bridgeport, in the county of Fairfield and State of Connecticut, have invented certain new and useful Improvements in Firing Mechanism, of which the following is a specification.

This application is a division of my application Serial No. 245,981, filed July 22nd, 1918, for Letters Patent for improvements in breech-loading magazine fire-arms, the several features of novelty in which, while applicable for the most part to magazine fire-arms in general, are designed particularly for and are illustrated as being embodied in a semi-automatic or recoil actuated fire-arm of the piston type.

More specifically stated, the invention herein claimed relates to certain improvements in the construction and relation of parts which go to make up the firing mechanism of such fire-arms, including the sear, the releasing connector therefor, the trigger for controlling said connector, the striker, and the safety member for preventing unintended release of the sear.

In the accompanying drawings:

Figure 1 represents a left side elevation of a fire-arm designed as a pistol and in which the several features of the present invention may be embodied.

Fig. 2 is a section of the fire-arm taken in an intermediate vertical longitudinal plane, the striker being cocked, and the lower portion of the grip being broken away.

Fig. 3 is a longitudinal sectional view of the upper portion of the pistol and showing parts on the opposite side of the plane of section from those shown in Fig. 2.

Fig. 4 is vertical transverse section through the upper portion of the pistol in about the plane of the sear and safety lever shaft.

Fig. 5 is a horizontal section in a plane through the trigger and above the sear-connector and showing the portion of the pistol adjacent said members.

Fig. 6 is a perspective view of the sear; 50 and

Fig. 7 is a rear elevational view of the trigger.

1 represents the frame; 2 the grip; 3 a barrel held against both rotary and longitudinal movement upon the frame by the lock-

ing block 4; 5 a breech-slide which extends the full length of the frame, and is mounted thereon to slide longitudinally relatively thereto, through means of the tongue and groove joints 6, and which is provided with the usual ejector opening 7; 8 the breech-closure removably inserted through the under side of the breech-slide but longitudinally fixed therein and carrying the striker 9; 10 the sear; 11 the trigger; 12 the trigger and sear connector; and 13 the extractor.

While each of these parts involves novelty in its construction and assembly in the fire-arm, so far as above described, each enters 70 into the organization for the same general purposes and in substantially the same functional relationship to the other parts as is common in fire-arms of this general type.

The sear.

The sear 10 embodies the peculiarity of having a substantially straight line or sliding movement transverse to the axis of the striker which it detains, so as to reduce to 80 a minimum any tendency to release the striker by a shock or a jar. This movement is preferably laterally transverse to the axis of the breech-slide; that is to say, the sear is supported vertically and longitudinally of the gun, and moves in a direction sufficiently near horizontal to render ineffective its inertia at times of either vertical or longitudinal jarring of the gun. As is shown in Figs.

6 and 4, it engages in front of a longitudinal extension 9^a on the under side of the striker by an end moving diagonally into engagement therewith, while the general direction of the sear in which it must move to release the striker is laterally and downwardly. By the rearward elongation of the projection 9^a the sear is held downward out of engaging position so long as the striker is forward of its cocked position, and the sear is thus maintained in readiness to snap up into arresting position whenever the striker is again moved rearwardly by the opening of the breech.

It will also be seen that the end of the sear remote from the striker intersects the outer surface of the frame, and since this outer end is designed to be flush with the surface when the sear is admitted to the recess 9^{ax} of the striker and the latter is cocked, but projects outwardly beyond the surface whenever the

striker is moved rearwardly, the sear is held in its proper position by the pressure of the frame against the outer end of the sear.

It will also be seen that the sear is held in its proper position by the pressure of the frame against the outer end of the sear.

105

110

striker is in a position to hold the sear out of the recess 9^{ax} , the outer end 10^a becomes an accurate and convenient indicator of the condition of the striker. Any suitable spring may be employed for normally pressing the sear 10 inwardly, as, for instance, the spring 10^b working in the recess of the horn 10^c of the sear, as shown in Fig. 6.

Sear safety.

The protrusion of the end 10^a of the sear 10 incident to its disengagement from the striker serves the further purpose of locking the sear against such displacement, and thus rendering the fire arm additionally safe when not in use. To accomplish this, a lever 30 , mounted upon a rotary shaft 30^a and extending transversely of the frame, may be moved from the position shown in Fig. 1 to a position overlying the projecting end 10^a , and when so adjusted, makes it impossible for the sear to move out of engagement with the striker. For the purpose of holding the lever 30 either in the position of Fig. 1 or in its sear-engaging position at substantially 90° thereto, a spring 30^b is introduced into the rear end of the frame in position to bear upon either of two flat faces 30^c or 30^d of said shaft, and so hold it reasonably in either position to which it may be moved.

Trigger and sear connector.

The connector interposed between the trigger and sear is moved longitudinally of the fire-arm by the trigger action, and displaces the sear by a camming action. This circumstance, coupled with the transverse sliding movement of the sear, is of especial importance in safeguarding the fire-arm against accidental displacement of the sear and release of the trigger. The connector is indicated at 12 . Its relation to the trigger 11 is best shown in Fig. 5, where it will be seen to have a transversely projecting end 12^a immediately behind the trigger and in position to receive the trigger spring 11^c , while it terminates at the rear in a camming end 12^b through which it coacts with the sear. Its control over the sear will be understood from Fig. 4, where it is shown passing through a notch in the under side of the outer end of the sear in such relation that as the connector moves rearwardly its cam face 12^b will force the sear outwardly and release the striker. The connector 12 has another movement, namely, a vertical movement by which it is caused to release the sear during the automatic action of the breech-slide, and so leave the sear ready to catch the striker and hold it in cocked position as the breach is closed. This displacement movement is imparted to a lug 12^e (Fig. 5) on the upper side of the connector 12 , which lies normally in the vertical plane

of the edge of the breech-slide, and is pressed downwardly thereby at all times, except when it coincides with the recess 5^e , as shown in Fig. 3. That is to say, when the parts are in the position shown in Fig. 3 the connector 12 may rise up under the tipping action of the trigger spring 11^c , for which effect the transverse projection 12^a is vertically elongated, as shown in Fig. 3, and so presents its rear end in controlling relation to the sear. When the trigger is pulled and the fire-arm recoils, rearward movement of the breech slide 5 passes the recess 5^e beyond the lug 12^e so that the under edge of the breech-slide cams down the connector 12 and so takes the rear end of the connector away from the sear and leaves the latter under control of its spring to engage in the recess 9^{ax} of the striker as the latter reaches it in the return or closing movement of the breech mechanism, and so that the striker will be held back to cocked position while the remainder of the breech mechanism continues forward to the breech-closing position.

I claim:

1. In a fire-arm, a frame having a longitudinal slide track, a breech slide reciprocating on said slide track, a striker moving longitudinally of said breech slide, and a sear having a bearing in the frame in which it slides endwise into and out of coaction with said striker; said sear and its slide bearing extending substantially laterally from the point of coaction with the striker to a position beneath the slide track.

2. In a fire-arm, a frame having a longitudinal slide track, a breech slide reciprocating on said slide track, a striker moving longitudinally of said breech slide, and a sear having a bearing in the frame in which it slides endwise into and out of coaction with said striker; said sear and its slide bearing extending substantially laterally from the point of coaction with the striker to a position beneath the slide track; and said sear having an outer end disposed in a side face of the frame.

3. In a fire-arm, a frame having a longitudinal slide track, a breech slide reciprocating on said slide track, a striker moving longitudinally of said breech slide, and a sear having a bearing in the frame in which it slides endwise into and out of coaction with said striker; said sear and its slide bearing extending substantially laterally from the point of coaction with the striker to a position beneath the slide track; and said sear being confined in its slide bearing by said breech slide.

4. In a fire arm, a longitudinally reciprocating breech slide, a striker moving longitudinally thereof, a sear sliding endwise into and out of detaining relation to said striker, in a direction later-

- ally and downwardly inclined thereto, and a frame having a longitudinal slide track for said breech slide and beneath said slide track, a laterally transverse slide bearing, confining said sear; said sear intersecting the outer lateral face of said frame. 5
 5. In a fire arm, a longitudinally reciprocating breech slide, a striker moving longitudinally thereof, a sear sliding endwise into and out of detaining relation to said striker, in a direction laterally and downwardly inclined thereto, a frame having a longitudinal slide track for said breech slide and beneath said slide track, a laterally transverse 10 slide bearing, confining said sear, a trigger mounted in said frame, and a trigger connector sliding longitudinally of the frame and transversely of the sear and having camming action upon the latter. 15
 10. In a fire-arm having a frame and a reciprocating breech-slide with a firing element incased therein, a sear mounted upon the frame and held thereto by means of the breech-slide; said sear moving into and out of engagement with the firing element by a straight line sliding movement in a downwardly inclined path substantially laterally 20 transverse to the longitudinal axis of the fire arm and reaching the firing element above without engaging the wall of the breech-slide in which the firing element is incased. 25
 20. In a fire arm, a longitudinally reciprocating breech slide, a striker moving longitudinally thereof, a sear sliding endwise into and out of detaining relation to said striker, in a direction laterally and downwardly inclined thereto, a frame having a longitudinal slide track for said breech slide and beneath said slide track, a laterally transverse slide bearing, confining said sear, a trigger mounted in said frame, and a trigger connector sliding longitudinally of the frame and transversely of the sear and having camming action upon the latter; said connector also having at its end adjacent the sear, a vertical movement to displace it from the sear, and said breech slide having displacing action upon said connector. 30
 30. In a fire arm having a grip, a reciprocating breech-closure and a striker mounted therein, a sear engaging and disengaging the striker by a sliding movement substantially laterally transverse to the longitudinal axis of the fire arm and intersecting a lateral surface of the fire-arm near the grip to indicate the position of the sear; said striker having a rearward projection, said striker overlying the sear and holding it out of engaging position when the striker is projected, and thereby causing the sear to indicate the position of the striker. 35
 40. In a fire-arm having a grip, a reciprocating breech-closure and a striker mounted therein, a sear engaging and disengaging the striker by a sliding movement substantially laterally transverse to the longitudinal axis of the fire-arm and intersecting a lateral surface of the fire-arm near the grip to indicate the position of the sear; and a safety member having an arm moving over the exterior surface of the fire-arm and adapted to overlie the exposed end of the sear when the striker is cocked. 45
 50. In a fire arm, a striker, a sear for said striker, a trigger connector coacting at one end with said sear but swinging at said end to separate it therefrom, a trigger, said connector and trigger having flat transverse faces through which they coact and by which when pressed together, the connector is pre- 55
 sented to the sear, and a spring pressing together said flat faces. 60
 9. In a fire-arm having a reciprocating breech-closure and a firing element incased therein, a sear engaging and disengaging the firing element by a sliding movement substantially laterally transverse to the axis of the bore of the fire-arm and inclined downwardly from the firing element, whereby it moves into engagement with the latter without engaging the walls of the breech-closure in which the firing element is incased. 65
 10. In a fire-arm having a frame and a reciprocating breech-slide with a firing element incased therein, a sear mounted upon the frame and held thereto by means of the breech-slide; said sear moving into and out of engagement with the firing element by a straight line sliding movement in a downwardly inclined path substantially laterally 70 transverse to the longitudinal axis of the fire arm and reaching the firing element above without engaging the wall of the breech-slide in which the firing element is incased. 75
 11. In a fire arm having a grip, a reciprocating breech-closure and a striker mounted therein, a sear engaging and disengaging the striker by a sliding movement substantially laterally transverse to the longitudinal axis of the fire arm and intersecting a lateral surface of the fire-arm near the grip to indicate the position of the sear; said striker having a rearward projection, said striker overlying the sear and holding it out of engaging position when the striker is projected, and thereby causing the sear to indicate the position of the striker. 80
 12. In a fire-arm having a grip, a reciprocating breech-closure and a striker mounted therein, a sear engaging and disengaging the striker by a sliding movement substantially laterally transverse to the longitudinal axis of the fire-arm and intersecting a lateral surface of the fire-arm near the grip to indicate the position of the sear; and a safety member having an arm moving over the exterior surface of the fire-arm and adapted to overlie the exposed end of the sear when the striker is cocked. 85
 Signed at Bridgeport, Conn., this 17 of May, 1919. 90
 ELBERT H. SEARLE. 105
